UNITED STATES PATENT OFFICE

2,499,302

EVAPORATOR

Fred W. Emhardt, Warren, Pa., assignor to
Struthers Wells Corporation, Warren, Pa., a
corporation of Maryland

Application December 6, 1943, Serial No. 513,143

6 Claims. (Cl. 159—28)

1

This invention relates to internally heated evaporators and is particularly directed to an evaporator construction providing directed flow of the liquid to be evaporated about the heating unit of the evaporator.

In liquid tube type evaporators wherein the liquid being evaporated is passed through tubes having the heating medium external thereto, it is common practice to provide means for increasing the rate of flow of the liquid through the tubes for the purpose of increasing the rate of heat transfer to the liquid, to reduce priming or foaming, and to reduce deposition of solids on the heating surfaces.

I have found that an increased velocity of liquid flow in internally heated evaporators with similar advantages can be obtained without the use of pumps, agitators or other power-driven devices by the construction of the invention which, in general, comprises the provision of one or more shrouds between the heating unit and the shell of the evaporator to provide a vertical boiling passage including the heating unit and one or more downtake passages between the shrouds and the shell of the evaporator and a deflector above the top opening of the boiling passage shaped to deflect liquid downwardly into the downflow passages. The heating units may comprise tube bundles or coils carrying a heating medium such as steam, oil, or the like, or electric heating elements.

A principal object of the invention, therefore, is the provision of an evaporator construction whereby a high rate of liquid circulation over the heating unit of an internally heated evaporator will be maintained.

Other objects and advantages of the invention will be apparent from the following description of illustrative embodiments of the invention with particular reference to the accompanying drawings in which:

Fig. 1 is an elevation in partial section of a vertical evaporator embodying the principles of the invention;

Fig. 2 is an elevation in partial section at right angle to the view of Fig. 1;

Fig. 3 is a transverse section on line 3—3 of Fig. 2 with parts broken away;

Figs. 4, 5 and 6 are views, corresponding to Figs. 1, 2 and 3, respectively, of another embodiment of the invention;

Fig. 7 is an elevation of a horizontal evaporator embodying the principles of the invention;

Fig. 8 is an end view of the evaporator of Fig. 7, and

Fig. 9 is a vertical section on line 9—9 of Fig. 7.

In Figs. 1 to 3, 10 is the shell of the evaporator, having in its lower portion a heating tube bundle 11, mounted in tube sheet 12 and supplied with

2

heating fluid, such as steam, Dowtherm or hot oil, through header 13.

Extending across the shell on each side of the tube bundle are vertical shroud members 14, providing in conjunction with the walls of the shell a boiling passage 15 surrounding the tube bundle and downflow passages 16 between the shrouds and the shell. The upper portions of the shrouds 14 are bent inwardly over a portion of the tube bundle, as shown, to provide slanting wall portions 14a.

Extending over the entire upper opening of the boiling passage 15 is a deflector 17 having its lateral edges bent downwardly over the upper ends of the shrouds 14 providing downwardly slanting wall portions 17a, as shown, to deflect liquid flowing out of the boiling passage downwardly into the downflow passages. As will be seen from reference to the drawings, the deflector 17 is so positioned in relation to the upper end of the shroud 14 that the wall portions 14a and 17a are disposed in adjacent confronting relation to define a downwardly and outwardly extending passage through which the vapors and entrained liquids must pass in travel from the boiling region 15 to the quiescent region 16.

By this construction a positive rapid flow of liquid upwardly through the boiling passage 15 is provided by the rising vapor bubbles which carry with them a quantity of liquid which is deflected back into the downflow passages 16 outside the confined heating unit. Foaming and priming is eliminated by impingement of the boiling stream against the deflector 17 and recirculation of the excess liquid into a quiescent, non-boiling region. The increased positive liquid circulation past the heating elements results in increased cleanliness of the heating surface. All of these factors result in a substantial increase in evaporating efficiency.

In the construction of Figs. 4—6, in which similar reference numerals are used for corresponding structural elements, the heating unit comprises a plurality of vertical coils 20 extending between upper header 21 and lower header 22.

The deflector 17 is provided with gutters 17', to drain deflected liquid back into the downflow passages without dropping it through the vapor stream passing out of the spaces between the deflectors and the upper ends of the shrouds, thus more effectively preventing entrainment of the liquid.

In the horizontal evaporator shown in Figs. 7—9, the tube bundle 11 is positioned along one side of the evaporator and the boiling passage 15 is provided between shroud 14 and the side of the shell 10. Deflector 17 projects over the top of the passage 15 from the side of the shell.

I claim:

1. An evaporator comprising a shell, a heating

unit in the lower part of the shell, a vertical shroud member disposed alongside said heating unit and spaced from the wall of said shell, said shroud member having an inwardly and upwardly inclined wall portion at the upper edge thereof and a deflector member disposed above and closely adjacent to said heating unit and shroud member, said deflector having a downwardly and outwardly inclined wall portion overlying and in adjacent confronting relation with respect to said inwardly and upwardly inclined wall portion of the shroud member, said shroud member dividing said shell into boiling and non-boiling regions and said shroud and deflector providing a confined space above the boiling region, and said adjacent inclined wall portions of the shroud and deflector members defining in cooperation a downwardly and outwardly directed passage connecting the confined space above the boiling region to the non-boiling region between the shroud and the shell while leaving ample space for vapors to rise in the shell after egress from said passage.

2. An evaporator comprising a shell, a heating unit in the lower part of the shell, a substantially vertical shroud member disposed alongside said heating unit and spaced from the wall of said shell thereby dividing said shell into boiling and non-boiling regions, said shroud member having an upwardly and inwardly inclined wall portion at the upper end thereof, and a deflector member disposed above and closely adjacent to said heating unit and shroud member, said deflector having a downwardly and outwardly inclined wall portion overlying and in adjacent confronting spaced relationship to said inclined wall portion of said shroud member and with its lowermost edges lying in the region of the horizontal plane through the top of the heating unit and at least substantially nearer said plane than the upper end of said shroud member, the downwardly and outwardly inclined wall portion of said deflector being adapted by its relative disposition to said inclined wall portion of the shroud member to cooperate therewith in defining a restricted positive path capable of directing a rapidly moving fluid stream from said boiling region downwardly and outwardly into said non-boiling region, and said shroud and deflector providing a confined space above said boiling region.

3. An evaporator comprising a shell, a heating unit in the lower part of the shell, a first vertical shroud member disposed alongside said heating unit and spaced from the wall of said shell, a second vertical shroud member alongside said heating unit and spaced from the wall of said shell on the opposite side of said heating unit from said first shroud member, said shroud members having inwardly and upwardly inclined wall portions at the upper edges thereof extending in converging directions above said heating unit, a deflector member disposed above and closely adjacent to said heating unit and shroud members, said deflector member having opposite downwardly and outwardly inclined wall portions overlying and in adjacent confronting spaced relation with said inwardly and upwardly inclined wall portions of said shroud members, said shroud members dividing said shell into a boiling region and non-boiling regions, said shroud and deflector members providing a confined space above the heating unit, and said inclined wall portions of the shroud members defining in cooperation

with the adjacent inclined portions of the deflector member downwardly and outwardly directed passages connecting the confined space above the heating unit to the non-boiling regions between the shroud members and the shell while leaving ample space for vapors to rise in the shell after egress from said passage.

5. An evaporator as defined in claim 3 wherein the opposite downwardly and outwardly inclined wall portions of said deflector member which are overlying and in adjacent confronting spaced relation with said inwardly and upwardly inclined wall portions of said shroud member are substantially parallel thereto.

10 6. An evaporator as defined in claim 3 wherein the deflector has intermediate its downwardly and outwardly inclined wall portions and substantially aligned with the center line of said heating unit a downwardly extending portion 20 V-shaped in transverse section formed by opposite inwardly sloping and converging surfaces and adapted to serve as a divider for an up-rising fluid stream in said boiling region.

15 7. An evaporator comprising a shell, a heating unit in the lower part of the shell, a vertical shroud member disposed alongside said heating unit and spaced from the walls of said shell, and defining therewith a non-boiling region and a boiling region including said heating unit, said shroud member having an upwardly inclined wall portion at the upper edge thereof extending inwardly of the boiling region, and a deflector member extending from the wall of said shell adjacent the boiling region and disposed above and closely adjacent to said heating unit and said shroud member, said deflector having a downwardly inclined wall portion extending outwardly of said boiling region into said non-boiling region and in overlying and adjacent confronting spaced 30 relation with said inwardly and upwardly inclined wall portion of the shroud member, said shroud and deflector members providing a confined space above said heating unit, and said adjacent inclined wall portions of the shroud and deflector 35 members defining in cooperation a downwardly inclined restricted passage connecting the confined space above the heating unit with the non-boiling region between the shroud and shell while leaving ample space for vapors to rise in the 40 shell after egress from said passage.

50 FRED W. EMHARDT.
